UNITED STATES PATENT OFFICE.

CHARLES E. VANCE, OF PITTSBURG, PENNSYLVANIA.

STEAM-TRAP.

No. 847,131.

Specification of Letters Patent.

Patented March 12, 1907.

Application filed December 20, 1906. Serial No. 348,737.

To all whom it may concern:

Be it known that I, CHARLES E. VANCE, a citizen of the United States, and residing in the city of Pittsburg, in the county of Allegheny and State of Pennsylvania, have invented or discovered new and useful Improvements in Steam-Traps, of which the following is a specification.

My invention consists in certain new and useful improvements in steam-traps whereby the contents of the trap when full is automatically discharged by the action of my improved valve mechanism, and after such discharge the valve automatically closes and remains closed until the trap fills once more. I also provide means for discharging the contents of the trap whenever desired and for holding the valve open at will. A novel construction and arrangement of parts is also shown.

In the accompanying drawings, Figure 1 is a vertical section of my steam-trap, showing the valve mechanism closed. Fig. 2 is a broken vertical section on a somewhat enlarged scale, showing the main valve closed and the relief-valve open. Fig. 3 is a similar view showing both main and relief valves open, while Fig. 4 is a cross-section along the line IV IV in Fig. 2.

The following is a detailed description of the drawings:

1 is the body of the casing of the trap, to which cover 2 is secured by any convenient means, such as bolts 3 3. A packing of any suitable character (not shown) may be introduced between the trap and cover to maintain a steam-tight joint.

4 is the inlet-port for live steam, preferably adjacent to the top of the casing. The steam-line is provided with the usual valve (not shown) to control the admission of steam into the trap.

5 is a curved baffle-plate downwardly depending within casing 1 in front of and in advance of port 4 to throw the entering steam toward the bottom of the casing to deposit the water contained therein. Said baffle-plate may either be made integral with cover 2 or may be attached, as shown, by any convenient means, such as by bolts 6 6 passing through plate 5 and engaging threaded holes in rib 7 integral with casing 1.

8 is a blow-out plug adjacent to the bottom of casing 1 to permit sediment deposited in the casing to be removed at will.

9 is a petcock in cover 2 to relieve the air-

pressure contained in the casing when the trap is put into service.

10 is the flanged opening in the center of cover 2, to the lower flange of which is secured, by threaded engagement, the downwardly-dependant tube 11.

12 is the bucket or receptacle contained within casing 1 and provided with central stem 13. Said stem has a reduced central portion, as shown, but at its lower end and adjacent to its top is of cross-sectional shape, substantially as shown in Fig. 4. The reason for such cross-sectional shape is to allow the water to flow up within tube 11 and at the same time to give said stem a firm bearing within said tube to steady the bucket in rising and falling. The stem 13 may be attached to the bucket 12 by any convenient means, such as by threaded engagement with collar 14, fixed to the under face of bucket 12.

15 is a cylindrical collar slidably mounted on stem 13 and provided with an annular flange 16 intermediate of its ends and having ports 15^a 15^a through the side wall thereof, as shown. 17 is annular washer or ring, adapted to fit down against said flange and provided with a flaring peripheral flange or lip, as shown.

18 is a valve-disk made of any suitable material, such as brass, and adapted to be slipped down over collar 15 against washer 17. The edges of said disk are provided with a flat bevel, as shown, the lower beveled edge being inclosed within the flaring flange of washer 17.

19 is a cylindrical jam-nut adapted to engage the screw-threads on the inner periphery of collar 15 and hold in place the disk 18 and washer 17 by means of an integral annular flange 20. The inner bore of nut 19 is beveled or flared at the bottom to form a valve-seat, as at 21.

22 is a small valve-plug rigidly held in threaded engagement with the upper end of stem 13. The upper end of said valve-plug is correspondingly beveled to engage valve-seat 21 when raised to the proper position.

23 is a flattened conical valve-seat, of brass or other suitable material, screwed into the upper portion of flanged opening 10, against which seat the disk 19 is forced when the valve is closed.

24 is a bonnet attached to cover 2 over opening 10 by any convenient means, (not shown,) such as suitable bolts, and 26 is a discharge-port in the side of said bonnet.

To said port 26 is coupled the waste-pipe, (not shown,) which may be provided with the usual valve to control the discharge.

27 is a cover in threaded engagement with 5 bonnet 24, having a central opening 28 in alinement with opening 10 in cover 2. Said opening 28 is internally threaded to engage worm 29 on stem 30, which extends through said opening, as shown in Fig. 1.

10 31 is a hand-wheel attached to the upper end of stem 30.

32 is a packing within the upper enlarged portion of aperture 28, which is compressed to form a steam-tight joint about stem 30 by 15 means of jam-nut 33, screwed down onto cover 27.

The operation of my trap is as follows: The steam is admitted through port 4 by 20 means of a suitable valve, (not shown,) the valve in the discharge-line leading from port 26 being closed. The petcock is opened for a moment to clear the trap of its contents of air and then closed. As the steam enters it is deflected downwardly by the baffle-plate 25 5 to the bottom of the casing, where it deposits its water. The cock in the discharge-line is now opened, and as the water accumulates in the bottom of the casing the bucket 12 floats upwardly until the valve mechanism 30 assumes the position shown in Fig. 1, thus completely closing opening 10 in the cover 2. As the water accumulates from the steam entering port 4 it gradually overflows the sides of bucket 12, gradually filling said bucket. 35 When sufficient water has accumulated in the bucket to cause it to sink in the water contained in casing 1, the stem 13 is carried down along therewith, withdrawing plug 22 from valve-seat 21, thus permitting a 40 balancing of pressure by escape through ports 15^a 15^a and the central bore of nut 19 and out of port 26. When the pressure within casing 1 has been thus reduced sufficiently to allow collar 15 to slip down on stem 13, the 45 disk 18 falls from engagement with valve-seat 23 and the elements of the valve mechanism assume the relative positions shown in Fig. 3. The opening 10 is now wide open and the steam-pressure within the casing forces 50 the water contained in bucket 12 up within tube 11 along stem 13, out opening 10 and port 26 to the waste. When sufficient water has been discharged from bucket 12 to allow it to again float, it will gradually rise until the 55 valve mechanism again assumes the position shown in Fig. 1, and thus remain until enough water has overflowed into the bucket to draw it down again and repeat the above-described operation. It is evident that the 60 bucket will automatically empty itself whenever it becomes filled. In case it is desired to empty the contents of the bucket before it becomes sufficiently loaded to automatically empty itself, I screw down stem 30 until the 65 lower end thereof pushes the valve mechan-

ism out of engagement with valve-seat 23, thus permitting the steam-pressure within the casing to drive the water contained in the bucket up tube 11 and out into the waste, or I may so adjust said stem 30 that at all times 70 said opening 10 is entirely or partially open to allow the water to be emptied as fast as it enters the bucket or rises above a desired height therein.

It is desirable at all times to maintain a 75 sufficient depth of water in bucket 12 to water seal the bottom of tube 11 against the entrance of steam therein. This may be effected by making said bucket of such weight that it will rise to its proper position to close 80 the valve mechanism while containing sufficient water to form the requisite water seal.

The object of forming valve-disk 18 of the double-beveled form shown to provide a reversible disk, so that when the beveled end 85 first put in use is worn the disk may be reversed and the unused bevel substituted. The flaring flange of washer 17 protects the unused beveled end from injury. The object of giving valve-seat 23 such a flattened 90 or gradual bevel is to enable the disk to find its proper engagement with the valve-seat notwithstanding any wobbling or unsteadiness of movement on the part of the rising bucket. 95

It is evident that many variations of the above construction may be substituted by those skilled in the art without departing from the scope and principles of my invention. I do not, therefore, confine myself to 100 the construction shown; but

I claim broadly—

1. In steam-traps, a discharge-opening in said trap, a tube communicating with said opening and downwardly depending within 105 said trap, a bucket within said trap, a stem attached to said bucket and upwardly extending within said tube, a collar slidably mounted on said stem, a valve-disk carried by said collar and adapted to engage said 110 opening, a valve-seat in said collar, a port in the wall of said collar beneath said valve-seat and a valve-plug rigidly mounted on said stem and adapted to engage said valve-seat.

2. In steam-traps, a discharge-opening, a 115 tube communicating with said opening and downwardly depending within said trap, a bucket within said trap, a stem attached to said bucket and upwardly extending within said tube, a collar slidably mounted on said 120 stem, a valve-disk mounted on said collar and adapted to engage said opening, a jam-nut engaging said collar and holding said disk in place, a valve-seat in said jam-nut, a 125 port in the wall of said collar beneath said valve-seat and a valve-plug rigidly carried by said stem adapted to engage said valve-seat.

3. In steam-traps, a discharge-opening, a 130 valve-seat in said opening, a tube communi-

- cating with said opening beneath said valve-seat and downwardly depending within said trap, a bucket within said trap, a stem attached to said bucket and upwardly extending within said tube, a collar slidably mounted on said stem, a valve-disk carried by said collar and adapted to engage said valve-seat, a jam-nut engaging said collar and holding said disk in place, a valve-seat in said nut, a port in the wall of said collar beneath said nut, a second valve-seat in said nut and a valve-plug rigidly mounted on said stem and adapted to engage said second valve-seat.
4. In steam-traps, a discharge-opening, a conical valve-seat secured in said opening, a tube communicating with said opening and downwardly extending within said trap, a bucket within said trap, a stem attached to said bucket and upwardly extending within said tube, a collar slidably mounted on said stem, a reversible valve-disk mounted on said collar and adapted to engage said valve-seat, a washer mounted on said collar and surrounding the lower portion of said valve-disk, a valve-seat in said collar, a port through the wall of said collar beneath said second valve-seat and a valve-plug rigidly mounted on said stem adapted to engage said second valve-seat.
5. In steam-traps, a discharge-opening, a conical valve-seat secured in said opening, a tube communicating with said opening and downwardly depending within said trap, a bucket within said trap, a stem attached to said bucket and upwardly extending within said tube, a collar slidably mounted on said stem, a reversible valve-disk mounted on said collar and adapted to engage said valve-seat, 25 a washer mounted on said collar and surrounding the lower portion of said valve-disk, a valve-seat in said collar, a port through the wall of said collar beneath said second valve-seat and a valve-plug rigidly mounted on said stem adapted to engage said valve-seat.
6. In steam-traps, a discharge-opening, a conical valve-seat secured in said opening, a tube communicating with said opening and downwardly depending within said trap, a bucket within said trap, a stem attached to said bucket and upwardly extending within said tube, a collar slidably mounted on said stem, a reversible valve-disk mounted on said collar and adapted to engage said valve-seat, 30 a washer mounted on said collar and surrounding the lower portion of said valve-disk, a valve-seat in said collar, a port through the wall of said collar beneath said second valve-seat and a valve-plug rigidly mounted on said stem adapted to engage said valve-seat.
7. In steam-traps, a discharge-opening, a conical valve-seat secured in said opening, a tube communicating with said opening and downwardly depending within said trap, a bucket within said trap, a stem attached to said bucket and upwardly extending within said tube, a collar slidably mounted on said stem, a reversible valve-disk mounted on said collar and adapted to engage said valve-seat, 35 a washer mounted on said collar and surrounding the lower portion of said valve-disk, a valve-seat in said collar, a port through the wall of said collar beneath said second valve-seat and a valve-plug rigidly mounted on said stem adapted to engage said valve-seat.
8. In steam-traps, a discharge-opening, a conical valve-seat secured in said opening, a tube communicating with said opening and downwardly depending within said trap, a bucket within said trap, a stem attached to said bucket and upwardly extending within said tube, a collar slidably mounted on said stem, a reversible valve-disk mounted on said collar and adapted to engage said valve-seat, 40 a washer mounted on said collar and surrounding the lower portion of said valve-disk, a valve-seat in said collar, a port through the wall of said collar beneath said second valve-seat and a valve-plug rigidly mounted on said stem adapted to engage said valve-seat.

Signed at Pittsburg, Pennsylvania, this 15th day of December, 1906.
